UNITED STATES PATENT OFFICE.

DANIEL SCHULTZ, OF PUEBLO, COLORADO.

MACHINE FOR TRIMMING AND FINISHING SEWER-PIPES AND THE LIKE.

1,249,520.

Specification of Letters Patent. Patented Dec. 11, 1917.

Application filed January 28, 1915. Serial No. 4,846.

To all whom it may concern:

Be it known that I, DANIEL SCHULTZ, a citizen of the United States, and a resident of Pueblo, in the county of Pueblo and State of Colorado, have invented a certain new and useful Machine for Trimming and Finishing Sewer-Pipes and the like, of which the following is a full, clear, and exact description.

10 This invention is a device for mechanically trimming and finishing tile, sewer pipe or like earthenware manufactures and its object is the provision of a mechanism for quickly and accurately trimming and finishing such articles as they come from the mold, thus avoiding a large portion of the labor of performing this operation by hand and obviating the irregularities and loss of product incidental to hand work. Broadly speaking 15 the invention comprises means for receiving and positioning the article to be finished, means for first cutting off extra length occurring at one end and means then coming into play for finishing the article and at the 20 same time for removing fins or "issue" at the other end.

Other and more detailed objects and advantages of my invention will later appear in this specification.

30 In the two sheets of drawings accompanying this application and forming a part hereof.

Figure 1 is a perspective of the entire machine, a portion of one of the side members 35 of the frame being broken away to disclose hidden parts;

Fig. 2 is an enlarged detail showing the fin cutting knife, the bell finishing means, and also illustrating the manner of detachably connecting the shafts carrying the finishing devices to the driving sprockets;

Fig. 3 is an enlarged detail in side elevation and vertical section showing the resilient connection for forcing the finishing 45 means to the work;

Fig. 4 is a similarly enlarged detail in side elevation showing the mounting of the spigot end finishing mechanism and the trimming mechanism while the latter is in 50 operative position (in this view, to avoid confusion of lines, the finishing mechanism has been shown as turned up vertically—a position it would not occupy in practice during the cutting operation); and

55 Fig. 5 is a diagrammatic view showing

the trimming mechanism in three of its positions as viewed from the front or bell end of the machine.

The entire machine is carried on a single frame A and a driving shaft 10, mounted in 60 bearings 11, extends from front to rear of the frame. I have shown a crank 12 for turning the shaft 10 and I prefer to employ this actuating means as being best suited to the nature of the work to be performed, 65 though it will be obvious that, if desired, power means could be substituted therefor without in any way departing from my invention. Fixed on the shaft 10 are front and rear sprockets 13, 14 on which run 70 chains 15, 16 which also run on the sprockets 17, 18 which are rotatably mounted on the short shafts 19 and 20 respectively, the shaft 19 being the one which carries the fin or issue knife 21 and the bell finisher 24, 75 which, in the case of a sewer pipe, finish the bell part of the pipe, and the shaft 20 carrying locked thereto by jamb nuts 22 the arm 23 which is provided at its outer extremity with the finishing tool 24.

80 Removably held in sockets 25 on the upper members of the frame A are work holding members 26 which are adapted to receive and hold the pipe or other article to be finished and to position the article with reference to the tools. This positioning in the case of the sewer pipe selected for illustration will, when the pipe is in final position, be performed by the rear of the bell B contacting with the front face of the first work 85 holding member 26 (which positioning has not as yet taken place in the illustration in Fig. 1) and by the fact that the centers of the semicircular concavities in the work holding members are in line with the centers of the short shafts 19, 20.

90 With the exception of the fact that the sprocket wheel 18 carries rigidly attached thereto the cutting tool carrying arm (as shown in Figs. 1 and 4) the mounting and 95 operation of the shafts 19, 20 and their attendant parts is identical. Each of the sprocket wheels 17, 18 has rigidly connected thereto a sleeve 28, formed with reduced portions 29 which are adapted to run in the 100 bearings 30 carried on the frame, and each sleeve is provided with opposed, flaring mouthed notches 31 adapted to engage and receive pins 32 on the shafts 19, 20, which 105 shafts are free to slide within the sleeves 28. 110

and which allow said sleeves to run free thereon except when the pins 32 are in engagement with the notches 31.

Means for imparting simultaneous longitudinal movement to the shafts 19, 20 toward and from the work are provided as follows: Straddling each shaft there is a yoke 33 the vertically slotted sides of which engage a pin 34 on a sleeve 35 slidably mounted on the shaft (see Fig. 3). On the side of the sleeve 35 which is toward the work there is a compression spring 36 coiled around the shaft and in engagement with the sleeve 35 and a washer 37, which washer is held firmly in position of the shaft as by a cotter pin 38 passing through the shaft. This connection is designed for the purpose of providing a slightly yielding means for forcing the finishing tools to the work, the advantage of which will be self-evident. On the side of the sleeve 35 away from the work there is a collar 39 rigidly set on the shaft, which collar will positively retract the shaft on movement of the yoke in the direction away from the work.

The several yokes 33 are carried on front and rear arms 34', 35' which are respectively non-rotatably mounted on shafts 36', 37' journaled in the frame. Means for rotating the shafts 36', 37' simultaneously in opposite directions are provided as follows: Between the shafts 36', 37' is a shaft 38' carrying oppositely extended arms 39', 40' which are connected by links 41, 42 with arms 43, 44 also non-rotatably mounted on the shafts 36', 37'. A lever 45 is so connected to the shaft 38' that depressing said lever will, through the train of mechanism described cause both yokes 33 to be swung in a direction toward the work.

As previously stated there is a trimmer carrying arm rigidly carried by the sprocket wheel 18. This arm preferably comprises a bent member 27 secured to the sprocket 18, a slotted plate 46 adjustably secured thereto, a rod 47 bolted to said plate and extending parallel to the axis of the shaft 20, a plate 48 pinned to the outer end of said rod and projecting at right angles thereto. The trimming blade 51 is secured to the plate 48 by being bolted to a member 49 which is pivotally attached to the plate 48 by a pin 50. The trimmer blade 51 is rigidly bolted to the member 49 and the latter is so shaped and proportioned as to have a limited swinging movement about the pin 50 (see Fig. 5) and to swing of its own weight as soon as the parts pass the top of the revolution around the axis of the shaft 20 and to remain out of line for approximately 270 degrees of the revolution. After passing substantially this point the tendency of the member 49 is to fall to the position shown in full lines in Fig. 5 and it is stopped there by the lug 52.

Operation.

The pipe P, green from the press, is placed in the sockets of the member 26 with the rear of its bell B in contact with the front face of the front member 26. Then the crank 12 is turned clockwise which drives the shaft 10 and the sprockets 17 and 18, which are now idle on their shafts. However, as previously stated, the arm 27 is rigidly attached to the sprocket 18 and therefore said arm and the cutting or trimming knife which it carries are caused to revolve. At the starting of the operation the knife 51 is in about the position shown in Fig. 1, which is also substantially that shown at X in Fig. 5. As the shaft 20 is rotated and the trimming parts revolve these latter will pass the point where gravity will maintain the member 49 and the knife 51 in said position and they will fall into the position shown in full lines in Fig. 5. Then the knife 51 will contact with the pipe and will cut off the excess in length which is provided at the spigot end. The resistance exerted against the knife 51 by the clay of the pipe will, during the time it is cutting, prevent its falling into the positions shown in dotted lines in Fig. 5 and the knife will remain in cutting position during the entire revolution. After the cutting revolution is complete and the knife passes the highest point in its travel it will again fall as shown at Y in Fig. 5 and thus be out of the way. I prefer, though this point is not essential to my invention, to proportion the sprocket wheels 14 and 18 in the ratio of 1 to 2 so that one revolution of the crank 12 will cause two revolutions of the sprocket 18 and the trimming mechanism. Then at the bottom of the turn 12 the cutting mechanism has made two complete revolutions and, having completely cut off the pipe, is back in starting position. I then depress the lever 45 which will throw the yokes 33 toward the work which will cause the pins 32 to enter the wide mouthed notches 31 on the sleeves 28 and fix the sprockets to the shafts, and at the same time advance the finishers 24 and 24^a and the finishing knife 21 to operative position. The pins 32 are so placed on the shaft 20 that the arm 23 will always clear the trimming mechanism; however, on account of the weight of the finisher 24 and the arm 23 and the fact that during the cutting operation the shaft 20 is idle, it so happens that generally the finisher 24 does not revolve during such cutting or trimming operation but hangs idly at the lower part of the circle and far enough toward the work to clear the arm 27 and the rod 47 (which latter is carried on a larger radius). Therefore in this preferred adjustment of parts, when the lever 45 is depressed the finisher 24 passes just behind the member 49 and holds

the knife 51 in the position shown at X in Fig. 5 during the entire revolution. This is not essential, however, for if the arm 23 should rotate (due to the friction between the sleeve 28 and the shaft 20) and the arm 23 be caught at 180 degrees from the cutting mechanism the knife 51 could do no harm in falling back to the full line position since it now clears the cut off pipe.

10 A turn now given the crank 12 will cause the finisher 24 to round off and finish the spigot end of the pipe and at the same time the finisher 24^a will act on the outer face of the bell and the knife 21 will trim off the fin 15 or issue which is formed on the inner edge of the bell in the process of molding. The pipe is now completed and is removed and the operation repeated, the shafts 19 and 20 being retracted to initial position by the 20 spring 53 which draws up the lever 45 when it is released.

It is important that the knife 51 should begin its cutting action at substantially the point indicated or at some analogous point 25 for the following reason: A part of the pipe end above the center line thereof should be the last to be severed to prevent a ragged break which would occur were all the upper part cut first. When the cutting takes place 30 as indicated contact will take place between the severed parts below the center line and brace the cut off portion and the last portion to be reached will be in tension instead of subject to a bending moment—which latter 35 would cause a ragged break and allow the parts of the pipe to separate much earlier than when cut as described.

It will of course be obvious that the tools 40 employed with my device may be changed to suit the work to be done and that if not needed some of the tools may be omitted without departing from my invention. Therefore I do not wish to limit myself to the particular forms and combinations 45 shown, other than is indicated by the appended claims, but what I do claim is:

1. In a device of the class described, a knife carrying arm, means for revolving said arm about the work, and a blade pivotally mounted in said arm in such position as 50 to tend to fall away from the work for a portion of the revolution of said arm.

2. In a device of the class described, a knife carrying arm, means for revolving 55 said arm about the work, and a blade pivotally mounted in said arm in such position as to tend to fall away from the work for a portion of the revolution of said arm and to

fall toward the work after passing a substantial distance above the center of revolution during the upward movement of said arm.

3. In a device of the class described, a knife carrying arm, means for revolving said arm about the work, a blade pivotally 60 mounted in said arm in such position as to tend to fall away from the work for a portion of the revolution of said arm and to fall toward the work after passing a substantial distance above the center of revolution 65 during the upward movement of said arm, and means for holding said blade in alignment when it meets with resistance from the work.

4. In a device of the class described, a 70 shaft, a driven sprocket wheel normally free on said shaft, a trimming tool carried by said sprocket wheel, a finishing tool carried by said shaft, and means for advancing said shaft to the work and fixing said sprocket to 80 said shaft.

5. In a device of the class described, a driving shaft, a pair of short shafts, a sprocket wheel on each short shaft and normally free to rotate thereon, means for driving said sprockets from said driving shaft, a trimming tool carried by one of said sprockets, a finishing tool carried by the short shaft on which said last mentioned sprocket is mounted, trimming tools carried 85 by the remaining short shaft, and means for simultaneously shifting said short shafts to bring said finishing tools into operative relation to the work and to fix the sprockets thereon.

6. In a device of the class described, a driving shaft, a pair of short shafts, a sprocket wheel on each short shaft and normally free to rotate thereon, means for driving said sprockets from said driving shaft, 100 a trimming tool carried by one of said sprockets, a finishing tool carried by the short shaft on which said last mentioned sprocket is mounted, trimming tools carried 105 by the remaining short shaft, and resilient means for simultaneously shifting said short shafts to bring said finishing tools into operative relation to the work and to fix the sprockets thereon.

In testimony whereof, I have hereunto affixed my signature in the presence of two 110 witnesses.

DANIEL SCHULTZ.
